UNITED STATES PATENT OFFICE.

THOMAS AARON EVANS, OF SAN FRANCISCO, CALIFORNIA.

ELECTRIC RAILWAY.

SPECIFICATION forming part of Letters Patent No. 425,767, dated April 15, 1890.

Application filed July 25, 1889. Serial No. 318,665. (No model.)

To all whom it may concern:

Be it known that I, THOMAS AARON EVANS, a citizen of the United States, residing in the city and county of San Francisco, and State 5 of California, have invented certain new and useful Improvements in Electric Railways, of which the following is a specification.

My invention relates to electric railways of that kind or construction in which a current-collector attached to the motor-car runs in electrical contact with an isolated underground rail or conductor; and the invention embraces a certain improved construction and arrangement of insulated conductor and underground tube, and also a novel construction of current-collector, all for operation and to secure several advantages, as hereinafter set forth.

In the following description, explaining the 20 nature of these improvements and the manner of constructing and applying them, reference is had by letters to the accompanying drawings, in which—

Figure 1 represents a transverse section of 25 the track and underground tube of an electric railway constructed according to my invention, and shows also in front view the truck and lower part of a motor-car and the current-collector mounted on it. Fig. 2 is a 30 top view in longitudinal section of a portion of the insulated conductor and the traveling current-collector in contact with it. Fig. 3 is a side view, on a larger scale, of the foot of the current-collector. Fig. 4 is an enlarged 35 sectional view of the traveler or current-collector.

The tube A has a slot a^x along the top for the shank or carrying bar of the current-collector, and the electrical conductor B is 40 laid along the tube against the top or roof and to one side of the tube-slot, being insulated from adjacent parts by the block C. A depending apron or partition D is fixed along the tube between the tube-slot and the conductor to shut off that part of the tube-space 45 for almost the full depth of the tube from the center portion, into which the tube-slot opens.

The current-collector E, traveling on and in electrical contact with the conductor B, is 50 fixed on the end of a carrying-bar F, which is mounted on the motor-car, and the bar is

formed with an offset or bend at the lower end, forming a laterally-extending foot F to pass beneath the bottom of the apron D and project into the space inside, where the conductor B is laid. 55

The current-collector is fixed to the upwardly-bent end of the foot F and consists of the grooved or double-flange wheels E^x , mounted on axles $g g$, for which bearings $h h$ 60 are provided in the end F^x of the shank-foot. The boxes are insulated from the side pieces F^x and have binding-posts $i i$ for conducting-wires $x x$, through which the current is carried from the wheels along the shank to a 65 point K on the upper part of the shank, where a connection is provided for the wires of the motor. The wires $x x$, being properly covered, may be laid in a groove in the face of the shank and brought upward to the binding- 70 posts on the block k . The shank is bolted at f^x to a screw-threaded shaft or round bar F^x , that is practically an extension of the flat shank, and is used in order to change the form of the bar in cross-section from flat to 75 cylindrical for the thread m . This threaded portion takes a hand-nut R, for which a bearing is furnished on the top plate L of the stand S. The top plate is circular with an opening 80 in the center for the upper part of the shank to pass loosely through, and between it and the top S^x a strong coil-spring T is placed, the top plate being held in place by long bolts $p p$ and nuts $q q$.

The legs of the supporting-stand are secured to the truck-frame or the body of the motor-car; but the shank has vertical movement in such support, as well as adjustability, by means of the threaded portion and its nut. 85

In this construction and arrangement it will be seen that the coil-spring bearing constantly upward against the hand-nut acts to keep the "trolley" E in contact with the insulated conductor in the tube under all 95 changes and conditions in the surface of the road as well as under varying movements of the motor-car in a vertical direction, and also that the current-collector, or "trolley," as I term it, can be adjusted by the hand-nut to 100 raise or lower it into or out of contact with the conductor. It is also lowered by the same

means clear of the apron when that point in the tube is reached where the man-hole or opening is provided for taking out the current-collector.

5 The apron should be carried down a suitable distance to insure complete protection of the conductor and trolley from mud, water, and dust entering through the tube-slot.

Having thus fully described my invention, what I claim, and desire to secure by Letters Patent, is—

The combination, with the stationary conductor B, of the trolley or traveler E, having

wheels E^x, mounted in insulated boxes, and the binding-posts having electrical connection 15 with the wheels, and the conducting-wire extending from said binding-posts to a binding-post on the shank in the car, as and for the purpose set forth.

In testimony that I claim the foregoing I 20 have hereunto set my hand and seal.

THOMAS AARON EVANS. [L. S.]
